UNITED STATES PATENT OFFICE.

TRYGVE E. MEYER, OF LOMBARD, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,351,531.

Specification of Letters Patent. Patented Aug. 31, 1920.

Application filed February 9, 1916, Serial No. 77,216. Renewed January 29, 1919. Serial No. 273,886.

To all whom it may concern:

Be it known that I, TRYGVE E. MEYER, a citizen of the United States of America, and a resident of Lombard, county of Du-
page and State of Illinois, have invented
certain new and useful Improvements in
Automatic Telephone Systems, of which the
following is a specification.

My invention relates to automatic tele-
10 phone systems and concerns itself more par-
ticularly with those automatic systems
which are made up, in part at least, of party
lines.

It is very desirable, in systems of the
15 above general character, to provide means
for extending calls for dead or changed
numbers to an operator via so-called traffic
trunks. In a system in common use the
connector switches having access to a cer-
20 tain group of party lines are divided into
sub-groups, the banks of the several sub-
groups being connected in multiple. Each
sub-group of connectors is provided with a
25 different frequency of ringing current cor-
responding to the different substations on
a party line. In case a substation on any
line is removed or the number changed, the
bank multiple from the corresponding
30 group of connectors is disconnected from
the line and is connected to a traffic trunk
extending to an operator's position. In this
way incoming calls for the disconnected
35 substation may be answered by an operator
without necessitating any change in the
numbers of the other parties on the line.

The above system is somewhat objection-
able because it requires many small groups
of connector switches, which groups are
necessarily inefficient. Efforts have been
40 made to reduce the total number of connector
switches required and so increase the
efficiency by combining the small sub-groups
of connectors having access to the same
group of party lines into one large group,
45 and by providing in addition, special fre-
quency selecting means associated with each
connector; but to the best of my present
knowledge these single group systems have
been more or less unsuccessful for the rea-
50 son that they provide no convenient way of
handling the dead number or traffic trunk
service.

It is the object of my invention to pro-
vide a practicable method of giving dead

number service without resorting to the in-
efficient grouping of connectors which has
been necessary heretofore.

I provide preferably, for each group of
party lines a single group of connector
switches, each connector switch containing
as many multiple contacts for each party
line as there are stations on the line. Each
connector switch is also provided with mul-
tiple sets of wipers and with relays which
are operated automatically to select the
proper set of wipers and the proper fre-
quency of ringing current. In case a cer-
tain substation is removed the connector
bank multiple corresponding thereto may
be readily shifted to a traffic trunk to enable
an operator to answer calls for that sub-
station.

To accomplish the foregoing and other
useful ends my invention comprises means
which will be hereinafter fully explained
and described, reference being had to the ac-
companying drawings, in which Figures 1,
2 and 3, taken in order with the lines at the
ends thereof in alinement, represent dia-
grammatically a complete circuit connec-
tion between a calling substation A and cer-
tain multiple contacts at the exchange allotted
25 to substation A² which contacts, how-
ever, have been disconnected from the line
of substation A² and are connected accord-
ing to my invention with a trunk line termi-
nating in a key K at an operator's position.
The said connection has been established
30 through the medium of the individual line
switch C, the selector switch E, and the con-
nector switch F.

Referring now to Fig. 1 the substation
A may be of any suitable or approved type
as, for example, the type disclosed in Brit-
ish patent to T. G. Martin, No. 1419 of 1910,
and as represented herein comprises the re-
ceiver 2, transmitter 3, switch hook 4, ringer
5, and condenser 6. Being an automatic
substation, there is also provided a pair of
impulse springs 7 and 8 and an impulse
wheel 9, which latter is assumed to be con-
trolled through the medium of a finger hole
dial (not shown).

Allotted to the line conductors 36 and 37
at the central exchange is an individual or
line switch C, which may be of the general
type of line switch shown in British patent
to James, No. 26,301 of 1906; being, how-

ever, more nearly of the particular type disclosed in British patent to Martin, No. 1419 of 1910.

Among other details, the line switch C 5 comprises a plunger (not shown) attached to the end of a so called plunger arm 18 which is controlled by the magnet 16. The magnet 16 has four windings, a pull-in winding 17, a cut-off winding 49, a line winding 38, and an auxiliary winding 12. The core of magnet 16 is so constructed that the magnetic circuit of windings 12 and 38 is independent of the magnetic circuit of windings 17 and 49. The winding 17 operates both 10 the plunger arm 18 and the cut-off armature 14 while the winding 49 is only strong enough to operate the armature 14 and to hold the plunger arm 18 in an operated position after it has been operated by the pull-in winding. The circuit of the pull-in winding is controlled by the armature 14 operated by the line winding 38 in conjunction with the auxiliary winding 12. When the plunger arm 18 is operated the plunger is 15 forced into a bank of springs, forcing the springs 39, 41, 43, and 45 into engagement, respectively, with contacts 40, 48, 44, and 46. Although only one set of springs and contacts (39-46) is shown, it is to be understood that each line switch is provided with 20 a plurality of such sets, each set forming the terminal of a trunk line leading to a selector switch similar to the selector switch E. Each trunk line is connected in multiple to 25 the corresponding springs of all the line switches of the group which is controlled by the master switch D.

The master switch D is of the same general type as that disclosed in British patent to 40 James No. 26,301 of 1906, above referred to; being, however, more nearly of the particular type disclosed in British patent to Martin, No. 1419 of 1910. The function of the master switch, as is well known, is to 45 maintain the plungers of all the idle line switches in position before the contact terminals of an idle trunk line.

The selector switch E is of the general 50 type of selector switch disclosed in United States Letters Patent No. 815,891, granted March 13, 1906, to Keith, Erickson, and Erickson; being, however, of the particular type disclosed in British patent to the Automatic Telephone Mfg. Co., No. 2543 of 55 1914. Among other details, the selector E comprises a bank of contacts arranged in horizontal rows or levels, which contacts are adapted to be engaged by a set of wipers 59, 67, and 68 carried upon a shaft (not 60 shown) which has a vertical movement controlled by the vertical magnet 51 and a rotary movement controlled by the rotary magnet 56. The operation of the various 65 parts of the switch is controlled through the medium of the double wound line relay 47.

Means for permitting the switch to be restored to normal position is provided in the release magnet 78 which, upon energizing, withdraws the retaining pawls from the shaft. The contacts 53 and 54 are closed 70 only when the shaft is raised one or more steps from its normal position. Relays 48 and 52 are slow acting, that is, they retain their armatures for an instant after their energizing circuits are broken. 75

As mentioned hereinbefore, I provide for each group of party lines a single group of connectors, each connector switch being provided with means for selecting the frequency of ringing current corresponding to the 80 party wanted. This selecting means is illustrated in Fig. 2 and comprises the relays 115 and 116 associated with the connector F. When a connector switch such as connector F is seized by a selector switch such as the selector switch E, one of the relays 115-116 will be operated and the relay operated depends upon the level to which the wipers of the selector switch are raised. This will be readily understood from a consideration of 85 the showing of bank contacts of the selector switch E in Fig. 1. Contacts a, b, and c are assumed to be the first set of contacts in the first level. Contacts a', b', and c' are assumed to be the first set of contacts in the 90 second level. The line contacts a and a' and c and c' are connected together and form terminals of conductors 26 and 27 extending to connector F. The private contacts b and b', however, are not connected but form 95 terminals of separate conductors 61 and 62 which extend to contact spring 181, relay 102 of connector F by way of relays 115 and 116, respectively. The remaining contacts in the first and second levels are connected 100 in a similar manner and form terminals of trunk lines extending to other connectors in the group of which connector F is one. The remaining levels in the bank of selector E, as for example, levels three and four, are 105 wired similarly to levels one and two and form terminals of trunk lines extending to other groups of connectors. 110

The connector F (Fig. 2) is of the general type of connector switch disclosed in 115 United States Letters Patent No. 815,176, granted March 13, 1906, to Keith, Erickson, and Erickson; being however, more nearly of the particular type disclosed in British patent to the Automatic Telephone Mfg. Co., 120 No. 2270 of 1914. Among other details the connector F comprises a bank of contacts arranged in horizontal rows or levels, which contacts are adapted to be engaged by a set of wipers 201, 202, and 203 carried upon a shaft 125 (not shown) which has a vertical movement controlled by the vertical magnet 103 and a rotary movement controlled by the rotary magnet 104. In accordance with my invention there is also provided a second bank of 130

contacts arranged in horizontal rows or levels and adapted to be engaged by a set of wipers 221 and 222 which are carried upon the same shaft with the first mentioned set. The two sets of wipers are, of course, operated simultaneously to engage corresponding sets of contacts in their respective banks, only one set being rendered effective for signaling and talking purposes, however, 10 as will appear more clearly hereinafter.

To continue with the description of the connector F, the various parts of the switch are controlled through the medium of the double wound line relay 100. The usual side 15 switch wipers 141 and 142 are controlled by the private magnet 107 in the regular manner. Means for permitting the switch to be restored to normal position is provided in the release magnet 113 which, upon energizing, withdraws the retaining pawls from the shaft and restores the side switch wipers to their first position. Springs 143 and 144 are controlled by the shaft and make contact with their respective contact points only 20 when the said shaft has been raised one or more steps from its normal position. Relays 102 and 106 are slow acting, that is, they are slow to retract their armatures when their respective energizing circuits are 25 broken. Various other relays not now specifically mentioned will be referred to in the detailed description of the operation.

Returning now to a more detailed description of the wipers and bank contacts shown 30 in Fig. 2, it will be seen that the connector F is provided with a private wiper, indicated by reference character 203, and with two sets of line wipers, indicated, respectively, by reference characters 201-202 and 40 221-222. The private wiper 203 is in service irrespective of the party called while but one set of line wipers is in service at a given time, as determined by the operation of the relays 115 and 116, before mentioned. 45 The sets of bank contacts 204-205-206 and 207-208-209 are located in the lower bank of connector F while the sets of banks contacts 224-225 and 227-228 are in the upper bank. Corresponding sets of contacts in the 50 upper and lower banks are normally connected in multiple as indicated by the conductors extending from contact set 227-228 to the line contacts of set 207-208-209. At some point in the multiple the normal conductors extending to the various lines accessible to connector F are attached. For example, the normal conductors 231, 232, and 233 are shown connected directly to contact set 204-205-206. Provision is made 55 whereby either the upper or lower set of line terminals corresponding to a given line may be disconnected from the multiple and therefore from the normal conductors of that line; and whereby a set of terminals, thus disconnected, 60 may be connected to a so called traffic

trunk, represented herein by conductors 234 and 235.

The traffic trunk, with other similar trunks, may be extended to an operator's position where each trunk terminates in a key, 70 such as key K, through the medium of which the associated trunk may be connected with the operator's head set indicated by reference character P.

In Fig. 3, I have shown two substations 75 A' and A'', the latter temporarily disconnected, and a pair of line conductors 300 and 301 extending to the exchange and there terminating in the individual line switch C'. The substations A' and A'' and the line 80 switch C' may be similar to substation A and line switch C (Fig. 1), already described, except that the ringers at substations A' and A'' are arranged to respond to different frequencies of ringing current. 85

For supplying current for operating and talking purposes I have shown a plurality of batteries B, B', etc., each battery having one terminal grounded. It will be understood that in actual practice there might well be 90 but one such battery. For supplying signaling current I have shown two generators R' and R''. It is understood that these generators supply currents of different frequency. Reference characters I and T indicate, respectively, an interrupter for intermittently operating the ringing relay 109 and other similar relays, and a busy signaling machine. 95

Having given a general description of the 100 apparatus, I will now proceed to an explanation of the operation of the same. For the purposes of this explanation it will be assumed that the subscriber at substation A desires to call the subscriber at 105 substation A'', which substation has been disconnected and the set of bank contacts 224-225, allotted thereto in the bank of connector F, has been connected to traffic trunk 234-235. Inasmuch as a great deal 110 of the apparatus shown herein is old and well known in the art, having been fully described in the publications referred to, its operation will be described in a more or less general manner, the details being given only 115 when they have to do with the application of the principles of my invention.

Upon the removal of the receiver at substation A, preparatory to making the call, a circuit is completed over the line conductors 36 and 37 for the line winding 38 of individual line switch C. Current flow in line winding 38 results in the attraction of armature 15, thereby completing a circuit for the pull-in winding 17 and the auxiliary 120 winding 12 in series. By the energization of the pull-in winding the plunger arm 13 and the cut-off armature 14 are attracted, the former through the medium of its plunger forcing the springs 39, 41, 43, and 45 125 130

into engagement, respectively, with contacts 40, 42, 44, and 46, and the latter disconnecting the line conductors 86 and 87 from their connection in the line switch C. It will be seen that the operation of the cut-off armature breaks the circuit of line winding 88, but the armature 15 is momentarily held attracted by current flow in the auxiliary winding 12. Upon the complete attraction of the plunger arm 18, the winding 12 is short circuited, thereby providing by means of the well known slow action for a further retention of armature 15 to allow time for establishing a holding circuit for winding 49 which will be described.

By the engagement of springs 89 and 48 with contacts 40 and 46, respectively, the line conductors 86 and 87 are extended to the line relay 47 of the selector E. Upon energizing, line relay 47 completes a circuit for slow acting relay 48 which relay, upon energizing in turn, completes a holding circuit for line switch O which may be traced as follows: ground at G¹, contact springs 21 and 20, contact 42, spring 41, and holding winding 49 to battery B. The holding winding 49, as before mentioned, retains the plunger arm 18 and cut-off armature 14 in operated position. A branch of the above holding circuit extends from spring 41 by way of conductor 50 to multiple test contacts in the banks of connector switches having access to the line of substation A by which a ground potential on these test contacts the said line is made busy to incoming calls. By the engagement of spring 43 with contact 44 the master switch B is operated in the well known manner to move the plungers of the other line switches in the group into position before the terminals of the next idle trunk line.

The foregoing operations have taken place in response to the removal of the receiver at substation A. The calling subscriber may now operate his calling device in accordance with the first digit of the desired number, whereby the impulse springs 7 and 8 are separated momentarily a number of times, interrupting each time the circuit of line relay 47 of selector E. As a result of these interruptions of its circuit the line relay 47 is deenergized a corresponding number of times, sending an impulse at each deenergization from ground at G² to the slow acting relay 48 and the vertical magnet 51 in series. The vertical magnet, in response to these impulses, steps up the shaft until the wipers stand opposite the proper horizontal level, which in this case is the level containing the bank contacts a', b', and c'. The relay 52, being slow acting, retains its armature during the series of impulses and closes a circuit for the test relay 55, which latter relay, upon attracting its armature, locks itself to ground at G³

and also prepares a circuit for the rotary magnet 56. At the end of the series of impulses the relay 52 deenergizes, thereby closing the aforementioned rotary magnet circuit, whereupon the wipers 59, 57, and 60 70 start rotating in search of an idle trunk line. As is well known, the rotary magnet interrupts its own circuit and also the locking circuit of the test relay 55 at every energization, the contacts in the latter circuit, 75 however, being short circuited by the test or private wiper 57 while passing over busy or grounded test contacts. As soon, therefore, as the test wiper reaches an ungrounded test contact the armature of test relay 80 55 falls back and opens the rotary magnet circuit, thereby bringing the wipers to rest upon the contacts of an idle trunk line, assumed to be in the present case the trunk line extending to connector F (Fig. 2). 85 Upon deenergizing, the test relay 55 also closes a circuit for the line switching relay 58, which latter relay disconnects the extended line conductors 86 and 87 from the windings of line relay 47 and further extends them by way of wipers 59 and 60 and conductors 26 and 27 to the line relay 100 of connector F.

The line relay 100 is now energized over the line circuit including substation A and, upon attracting its armature, completes an energizing circuit for the slow acting relay 102. Relay 102, upon energizing, completes a holding circuit for the line switching relay 58 of selector E and the holding winding 49 100 of line switch C as follows: ground at G⁴, contact springs 180 and 181, winding of relay 116, conductor 62, bank contact b', and wiper 57 to wire junction 24, where the circuit divides, one branch extending by way 105 of contact springs 80 and 81 and the winding of line switching relay 58 to battery B, and the other branch extending by way of off normal contact 53 and interrupter contact 82 to wire junction 25, where it joins the 110 previously described holding circuit of line switch C, about to be opened at contact springs 20 and 21 of slow acting relay 48.

Relay 116 is energized by current flow in the above described holding circuit and attracting its armature, determines the set of wipers and the frequency of ringing current to be used by connector F. In order not to greatly reduce the ground potential upon the various multiple test contacts made busy over the holding circuit the relays 116 and 115 are of rather low resistance.

The calling subscriber at substation A may now operate his calling device in accordance with the second digit of the desired 125 number, resulting at this stage of the operation, in deenergizations of line relay 100 of the connector F. At each deenergization, the line relay 100 sends an impulse from ground at G⁵ to the slow acting relay 106 130

and the vertical magnet 103 in series, side switch wiper 141 being in its first position. The vertical magnet in response to these impulses, steps up the shaft until the wipers 5 221 and 222 stand opposite the horizontal level of the upper bank in which are located the set of contacts allotted to substation A'. At the same time, of course, the wipers 201, 10 202, and 203 are raised opposite the corresponding level in the lower bank. The relay 106, being slow acting, retains its armature during a series of impulses and maintains an energizing circuit for the private magnet 107. At the end of the series of impulses the 15 relay 106 and the private magnet 107 deenergize, the latter controlling the side switch wipers 141 and 142 in the usual manner to advance them to their second position.

The calling subscriber at substation A 20 may now operate his calling device in accordance with the third and final digit of the desired number, resulting as before in deenergizations of the line relay 100. At this stage of the operation, however, side switch wiper 141 being in its second position, the line relay 100 sends impulses to the slow acting relay 106 in series with the rotary magnet 104, whereby the wipers 221 and 222 are rotated until they arrive at upper 25 bank contacts 224 and 225, respectively. At the same time the wipers 201, 202, and 203, are rotated until they arrive at lower bank contacts 204, 205, and 206. The wipers 201 and 202, since the conductors attached there- 30 to are open at contacts of relay 115, are without function at this time. During the last series of impulses the private magnet was operated as before through the medium of relay 106, whereby, at the end of the series 35 of impulses, the side switch wipers are advanced to their third position (it being assumed that the line called was idle at the time).

As side switch wiper 142 comes into its 40 third position, a circuit is completed from ground at G', by way of wiper 203, bank contact 206 and conductor 232 to holding winding 249 of line switch C'. Upon energizing, the holding winding 249 operates the cut-off armature 214, whereby the line conductors 300 and 301 are disconnected from their connections in line switch C'. Ground from G' is also extended to multiple contacts similar to contact 206 in the banks of other connectors of the group, thereby making the line busy to other calls.

As a further result of the advance of side switch wiper 142 to its third position a circuit is completed for the relay 110 over the 45 following path: ground at G', side switch wiper 142 in third position, contact springs 152 and 151, and winding of relay 110 to battery B. Upon attracting its armature, relay 110 completes the following circuit for 50 the back bridge relay 114; ground at G',

winding 117 of relay 114, contact springs 156 and 155, contact springs 160 and 159, contact springs 161 and 162, wiper 221, bank contact 224, conductor 235, winding of relay 210, conductor 234, bank contact 225, wiper 222, contact springs 163 and 164, contact springs 157 and 158, contact springs 153 and 154, and winding 118 of relay 114 to battery B. Upon the closure of the above circuit, relays 114 and 240 attract their armatures, the former relay completing a circuit in the usual manner for the ring cut-off relay 108, which latter relay, upon attracting its armature, establishes a locking circuit for its winding and also opens a contact in the circuit of ringing relay 109, now closed at side switch wiper 141, third position. It has been assumed in the foregoing that the circuit through interrupter I was open when the side switch wipers advanced to third 55 position; if this circuit has been closed the ringer relay would have been energized first and the circuit of back bridge relay 114 would not have been closed until the first deenergization of the ringing relay. 60

When the relay 240 attracts its armature, a circuit is completed for the lamp 241 in an obvious manner, thereby indicating to the operator that a call has been received. By operating the key K the operator may 65 bridge her head set P across the trunk conductors 234 and 235. Conversation may now be held over the talking circuit indicated clearly by the heavy conductors, talking battery being supplied to the transmitter at substation A through the windings 70 of the line relay 100.

Upon learning the number of the subscriber wanted, it is the duty of the operator to look this number up to ascertain 75 whether it is in service or not. Finding that the telephone of the subscriber wanted has been disconnected, she so informs the calling subscriber who, understanding that he cannot get his party, replaces his receiver on the hook. When the receiver is replaced the energizing circuit of line relay 100 is broken, whereupon all the switches in use are disconnected and restored to normal position in the well known manner. 80

If the calling subscriber at substation A desires to connect with substation A', which substation is not disconnected, the digits called will be the same with the exception of the first digit. By calling a digit one less than the one called in the previously described connection the wipers 59, 57, and 60 of the selector E will be raised to the level containing contacts a, b, and c after which they are rotated to pick out an idle 85 trunk. Since but one group of trunk lines terminate in the levels shown, it is evident that the call will be extended to a connector in the same group as before. Assuming that the trunk line represented by contacts 90

6
a, b, and c is found idle then the same connector used in the previously described case, connector F, will be seized. It will be seen, however, that since the private wiper 57 is 5 now in engagement with contact b the holding circuit for the selector and line switch will be completed by way of conductor 61 instead of conductor 62, thereby resulting in the energization of relay 115 of connector F.

10 The calling subscriber may now operate his calling device in accordance with the remaining two digits of the desired number which two digits are the same as the last 15 two digits of the number of substation A², previously called. It follows that connector F is operated precisely in the manner before described, the two sets of wipers being raised and rotated onto the same sets of 20 contacts as before. Now, however, relay 115 being energized instead of relay 116, the set of line wipers 201 and 202 is rendered active while the set 221 and 222 remains open at contacts of relay 116. The ringing 25 relay is now operated intermittently to project ringing current from generator R² out over the line extending to substation A' to signal the called subscriber. Upon hearing his bell the subscriber at substation A' 30 removes his receiver, thereby completing, at the first deenergization of the ringing relay, a circuit for the back bridge relay 114. The back bridge relay, upon energizing, operates as before to close a circuit for 35 the ring cut-off relay 108 whereby the ringing operation is stopped. The method by which conversation may be held between the two substations and the connection finally released being obvious from the drawings 40 and from the previous description it is not thought to be necessary to go further into the details.

Nor will it be necessary to describe in detail the operation when a busy line is 45 called, it being well known that in a connector switch of the general type described herein, when the test wiper stops on a busy or grounded test contact, the side switch wipers are locked in second position to prevent connection with the called line. Also, 50 by the operation of the busy test relay 105 a distinctive tone from the busy signaling machine T is transmitted over the calling line by which the calling subscriber is informed that the wanted line is busy.

55 It will be seen from the foregoing that I have devised a simple and efficient method by which a single group of connector switches may be adapted to serve a group 60 of party lines without omitting the desirable features of selective ringing and traffic trunk service, thereby tending to increase the general efficiency and practicability of an automatic telephone system.

65 While I have found it convenient, in

explaining my invention, to show a certain specific embodiment thereof I do not wish to be held strictly to the exact form shown herein, for various adaptations will no doubt present themselves to persons skilled in the art. I desire, therefore, to include and have protected by Letters Patent all forms and modifications of my invention which may come within the scope of the appended claims.

70
75
What I claim as my invention is:

1. In a telephone system, a party line having a plurality of substations, signals at said substations responsive to signaling currents of different character, a multiple 80 line terminal corresponding to each substation, a connector switch having a plurality of movable terminals co-operating with said line terminals, means for operating said connector to bring its movable terminals 85 simultaneously into engagement with said line terminals, sources of signaling currents of different character, and means for selecting a movable terminal and a source of signaling current whereby said substation signals 90 may be operated selectively.

2. In a telephone system, a plurality of party lines each having substation signals responsive to signaling currents of different character, a fixed multiple terminal at the 95 exchange corresponding to each substation of each line, a connector switch having movable terminals and means for operating them to simultaneously connect with all the fixed terminals for a given line, sources of 100 signaling currents of different character, and means for selectively associating said signaling current sources with the connected line through the medium of selected movable terminals whereby substation signals 105 may be operated selectively.

3. In a telephone system, a plurality of party lines each having substation signals responsive to signaling currents of different character, connector switches for extending 110 connection to said lines, multiple terminals for said lines in said connector switches, there being a separate terminal in each connector for each substation on each line, movable terminals in each connector and means 115 for operating them to simultaneously engage all the multiple terminals of a given line, sources of signaling currents of different character, and means for selecting the proper signaling current source and 120 movable terminal whereby said substation signals may be operated selectively.

4. In a telephone system, a party line having a plurality of substations, signals at said substations responsive to signaling currents of different character, a multiple line terminal corresponding to each substation, a connector switch having a plurality of movable terminals co-operating with said line terminals, means for operating said con- 125 130

- 5 connector to bring its movable terminals simultaneously into engagement with said line terminals, a different source of signaling current associated with each movable terminal, and means for selecting one of said movable terminals and its associated signaling current source before the operation of said connector whereby said substations may be signaled selectively.
- 10 5. In a telephone system, a plurality of party lines each having substation signals responsive to signaling currents of different character, a fixed multiple terminal at the exchange corresponding to each substation of each line, a connector switch having movable terminals and means for operating them to simultaneously connect with all the fixed terminals for a given line, a different source of signaling current associated with each movable terminal, and means for selecting one of said movable terminals and its associated signaling current source before the operation of said connector whereby said substations may be signaled selectively.
- 15 6. In a telephone system, a plurality of party lines each having substation signals responsive to signaling currents of different character, connector switches for extending connection to said lines, multiple terminals for said lines in said connector switches, there being a separate terminal in each connector for each substation on each line, movable terminals in each connector and means for operating them to simultaneously engage all the multiple terminals of a given line, separate sources of signaling currents of different character, each associated with similarly positioned movable terminals in the several connectors, and means operated before the operation of any connector for selecting one of its movable terminals and the associated signaling current source, whereby said substations may be signaled selectively.
- 20 7. In a telephone system, a plurality of party lines each having substations and signals responsive to signaling currents of different character, a connector switch having fixed multiple line terminals arranged in a series of banks, there being in each bank a multiple terminal of each line, a plurality of movable terminals in said connector one of which cooperates with the fixed terminals in each bank, a different source of signaling current associated with each movable terminal, and means for selecting and operating said movable terminals whereby said substations may be signaled selectively.
- 25 8. In a telephone system, a plurality of party lines each having substations with signals responsive to signaling currents of different character, a multiple line contact for each substation on each line, said contacts arranged in banks in accordance with the several characters of signaling current to which their associated substations are adapted to respond, a connector switch having a separate wiper for each bank, sources of signaling current of different character, one for each bank and co-operating wiper, and means for connecting any one of said sources with any one of said lines through the medium of one of said wipers whereby said substations may be signaled selectively.
- 30 9. In a telephone system, a plurality of party lines each having substations with signals responsive to signaling currents of different character, a multiple line contact for each substation on each line, said contacts arranged in banks in accordance with the several characters of signaling current to which their associated substations are adapted to respond, a connector switch having a separate wiper for each bank, a different source of signaling current corresponding to each wiper, means for selecting one of said sources, and means for connecting the selected source, through the medium of the corresponding wiper, with a wanted line to signal a wanted substation thereon.
- 35 10. In a telephone system, a plurality of party lines, each having a certain number of substations, signals at said substations responsive to signaling current of different character, fixed multiple terminals for said lines at the exchange, there being as many multiple terminals for each line as there are substations on a line, a connector switch having as many movable terminals as there are multiple terminals per line, each movable terminal co-operating with corresponding fixed terminals of the several lines, a different source of signaling current associated with each of said movable terminals, and means associated with said connector for selecting movable terminals and operating them, whereby said substations may be signaled selectively.
- 40 11. In a telephone system, a party line having a plurality of substations, a fixed multiple terminal corresponding to each of said stations, a connector switch having movable terminals and means for operating them to connect simultaneously with all of said fixed terminals, a selector switch, a trunk line extending from said selector to said connector and having a plurality of terminals in the selector, means for operating said selector to connect with one of said trunk terminals, and means dependent upon the terminal connected with by said selector for selecting one of said movable connector terminals.
- 45 12. In a telephone system, a party line having a plurality of substations, a fixed multiple terminal corresponding to each of said stations, a connector switch having movable terminals and means for operating them to connect simultaneously with all of said first terminals, a selector switch, a trunk

line extending from said selector to said connector and having a plurality of terminals in the selector, means for operating said selector to connect with one of said trunk terminals, and means dependent upon the terminal connected with by said selector for selecting one of said movable connector terminals, said last means comprising a relay for each movable connector terminal.

13. In a telephone system, a party line having a plurality of substations provided with signals responsive to ringing currents of different character, a fixed multiple terminal corresponding to each of said substations, a connector switch having a movable terminal coöperating with each fixed terminal, sources of ringing current of different character, one for each movable connector terminal, a selector switch, a trunk line extending from said selector to said connector and having a plurality of terminals in the selector, means for operating said selector to connect with one of said trunk terminals, and means dependent upon the trunk terminal connected with by said selector for selecting a movable connector terminal and the corresponding ringing current source.

14. In a telephone system, a party line having a plurality of substations provided with signals responsive to ringing currents of different character, a fixed multiple terminal corresponding to each of said substations, a connector switch having a movable terminal coöperating with each fixed terminal, sources of ringing current of different character, one for each movable connector terminal, a selector switch, a trunk line extending from said selector to said connector and having a plurality of terminals in the selector, means for operating said selector to connect with one of said trunk terminals, and means dependent upon the trunk terminal connected with by said selector for selecting a movable connector terminal and the corresponding ringing current source, said last means comprising a relay for each movable connector terminal, each relay adapted to close connections for its associated movable terminal and the corresponding ringing current source.

15. In a telephone system, a plurality of party lines, each having substations with signals responsive to signaling currents of different character, selector and connector switches at the exchange, banks of called line terminals for said substations in said connectors, said banks subdivided and the terminals arranged therein in accordance with the character of signaling current to which their associated substations are adapted to respond, a movable terminal in each connector coöperating with each of its bank subdivisions, sources of signaling current of different character, means controlled by a calling line for operating a selector and

connector by series of impulses to connect with a called line, and means dependent for its operation upon the number of impulses in the series controlling the said selector switch for selecting a movable terminal of the said connector switch and one of said sources.

16. In a telephone system, a plurality of party lines, each having a plurality of substations some of which are disconnected from their respective lines, a connector switch having a contact bank containing a particular contact for each substation, a trunk line, connections from each party line to the contacts corresponding to its connected substations, and connections from said trunk line to the contacts corresponding to disconnected substations, whereby upon the operation of said connector to connect with a disconnected substation connection will be established with said trunk line instead.

17. In a telephone system, a plurality of party lines, each having a plurality of substations some of which are disconnected from their respective lines, a connector switch having a contact bank containing a particular contact for each substation, a trunk line, connections from each party line to the contacts corresponding to its connected substations, and connections from said trunk line to the contacts corresponding to disconnected substations whereby upon the operation of said connector to connect with a disconnected substation connection will be established with said trunk line instead, and manually controlled means associated with said trunk line for answering calls received thereover.

18. In a telephone system, a party line having a plurality of substations, a connector switch at the exchange having a plurality of contact banks, a contact in each bank for a different one of said substations, multiple connections from said line to said contacts, means for disconnecting any contact from its multiples, and a trunk line extending to an operator's position adapted for connection to such disconnected contact.

19. In a telephone system, a plurality of party lines each having a plurality of substations, a connector switch at the exchange having a plurality of contact banks, contacts for said substations in said banks, the substations on the same line having their contacts in different banks, multiple connections from each line to the contacts corresponding to its several substations, means for disconnecting the contact corresponding to any substation from its multiple connections, and a trunk extending to an operator's position adapted for connection to said disconnected contact.

20. In a telephone system, a plurality of party lines each having a plurality of sub-

- stations, a plurality of connector switches at the exchange each having a plurality of contact banks, multiple contacts for each substation in the banks of said connectors, the 5 substations on the same line having their contacts in different banks in the same connector, multiple connections from each line to the multiple contacts corresponding to its several substations, means for disconnecting 10 the multiple contacts corresponding to any substation from their connection to the line for that substation, and a trunk extending to an operator's position adapted for connection to said disconnected contacts.
- 15 21. In a telephone system, a party line having a plurality of substations, a connector switch at the exchange having a plurality of contact banks, a contact in each bank for a different one of said substations, multiple 20 connections from said line to said contacts and a trunk line, said contacts adapted to be separately disconnected from the line and connected instead to said trunk line.
22. In a telephone system, a plurality of 25 party lines each having a plurality of substations, a connector switch at the exchange having a plurality of contact banks, contacts for said substations in said banks, the substations on the same line having their 30 contacts in different banks, multiple connections from each line to the contacts corresponding to its several substations, and a trunk line, said contacts adapted to be separately disconnected from their respective 35 multiple connections and connected instead to said trunk line.
23. In a telephone system, a plurality of party lines each having a plurality of substations, a plurality of connector switches at 40 the exchange each having a plurality of contact banks, multiple contacts for each substation in the banks of said connectors, the substations on the same line having their contacts in different banks in the same connector, multiple connections from each line to the multiple contacts corresponding to its several substations, and a trunk line, said contacts adapted to be separately disconnected from their respective multiple 45 connections and connected instead to said trunk line.
24. In a telephone system, a party line having two substations, one of said substations disconnected, a connector switch at the exchange having a pair of contact banks, a contact corresponding to one substation in one bank, a contact corresponding to the other substation in the other bank, connections from said line to the contact corresponding 55 to the connected substation, a trunk extending to an operator's position, and connections from said trunk to the contact corresponding to the disconnected substation, wipers in said connector coöperating with its several contact banks, and means for selecting wipers and operating them when selected whereby connection may 60 be established either with the connected substation or with said trunk line.
25. In a telephone system, a plurality of party lines, each having a plurality of substations, certain of said substations disconnected from their respective lines, a connector switch at the exchange having a plurality of contact banks, contacts corresponding to said substations in said banks, the substations on the same line having their contacts in different banks, connections from each line to the contacts corresponding to its several connected substations, a trunk extending to an operator's position, and connections from said trunk to the contacts corresponding to the several disconnected substations.
26. In a telephone system, a plurality of party lines, each having a plurality of substations, certain of said substations disconnected from their respective lines, a plurality of connector switches at the exchange each having a plurality of contact banks, multiple contacts for each substation in the banks of said connectors, the substations on the same line having their contacts in different banks in the same connector, connections from each line to the multiple contacts corresponding to its several connected substations, a trunk line extending to an operator's position, and connections from said trunk line to the contacts corresponding to the several disconnected substations.
27. In a telephone system, a party line having two substations, one of said substations disconnected, a connector switch at the exchange having a pair of contact banks, a contact corresponding to one substation in one bank, a contact corresponding to the other substation in the other bank, connections from said line to the contact corresponding to the connected substation, a trunk extending to an operator's position, and connections from said trunk to the contact corresponding to the disconnected substation, wipers in said connector coöperating with its several contact banks, and means for selecting wipers and operating them when selected whereby connection may be established either with the connected substation or with said trunk line.
28. In a telephone system, a plurality of party lines, each having a plurality of substations, certain of said substations disconnected from their respective lines, a connector switch at the exchange having a plurality of contact banks, contacts corresponding to said substations in said banks, the substations on the same line having their contacts in different banks, connections from each line to the contacts corresponding to its several connected substations, a trunk extending to an operator's position, and connections from said trunk to the contacts corresponding to the several disconnected substations, wipers in said connector coöperating with its several contact banks, and means for selecting wipers and operating them when selected whereby connection may be established either with the connected substation or with said trunk line.

nection may be established either with connected substations or with said trunk line.

29. In a telephone system, a plurality of party lines, each having a plurality of substations, certain of said substations disconnected from their respective lines, a plurality of connector switches at the exchange, each having a plurality of contact banks, multiple contacts for each substation in the banks of said connectors, the substations on the same line having their contacts in different banks in the same connector, connections from each line to the multiple contacts, corresponding to its several connected substations, a trunk line extending to an operator's position, and connections from said trunk line to the contacts corresponding to the several disconnected substations, wipers in said connectors co-operating with their respective contact banks and means for selecting wipers and operating them when selected whereby connection may be established either with connected substations or with said trunk line.

30. In a telephone system, a switch, a plurality of brushes on said switch, a connecting circuit extending to said switch, multiple terminals for said connecting circuit at which said circuit may be selected, and means dependent on which of said multiple terminals said switch is selected for determining which of said brush sets will be rendered operative.

31. In a telephone system, a switch, a plurality of sets of brushes for said switch, groups of telephone line contacts arranged for engagement by said brushes respectively, a connecting circuit extending to said switch, multiple terminal contacts for said connecting circuit, movable contacts for making connection with said terminal contacts, and means for determining which of said brush sets will be rendered operative controlled by said movable contacts being engaged with one or another of said multiple terminal contacts.

32. In a telephone system, a switch, a plurality of sets of brushes for said switch, groups of telephone line contacts arranged for engagement by said brushes respectively, brush selecting means for rendering one or another of said brush sets operative, a connecting circuit extending to said switch, two series of multiple terminal contacts for said connecting circuit, movable contacts for making connection with said terminal contacts, and means whereby the operation of said brush selecting means is controlled by said movable contacts being engaged with one or another of said series of multiple terminal contacts.

33. In a telephone system, a switch, a plurality of brush sets on said switch, series of contacts, one for each of said brush sets, means for selecting one of said brush sets

to make connections to a wanted line, a plurality of sources of ringing current of different characters, and means controlled by said brush selecting means for determining which of said sources of current will be connected to a wanted line.

34. In a telephone system, a switch, a plurality of brushes on said switch, a connecting circuit extending to said switch, multiple terminals for said connecting circuit at which said circuit may be selected, means dependent on which of said multiple terminals said switch is selected at for determining which of said brush sets will be rendered operative, a plurality of sources of ringing current of different characters, and means controlled by said brush determining means for connecting one or another of said sources of current to a selected brush set.

35. In a telephone system, an automatic connector switch, a party line accessible to said connector via as many paths as there are stations on the line, means for operating said connector to connect with said line, and means operated automatically when the connector is seized for predetermining over which path the connection is to be established.

36. In a telephone system, an automatic connector switch, a party line accessible to said connector via as many paths as there are stations on the line, a corresponding plurality of generators of different electrical character, means in said connector for selecting one of said generators for connection to said line, and means operated automatically when the connector is seized for predetermining the path over which the selected generator is to be connected.

37. In a telephone system, an automatic connector switch, a party line accessible to said connector via as many paths as there are stations on the line, means for operating said connector in accordance with two digits in the call number of said line to connect therewith, and means for predetermining in accordance with a previous digit the path over which the connection is to be established.

38. In a telephone system, an automatic connector switch, a party line accessible to said connector via as many paths as there are stations on the line, a corresponding plurality of generators of different electrical character, means for connecting any generator with said line, and means in said connector operated automatically when the connector is seized for selecting a generator and for predetermining the path over which it is to be connected in accordance with a digit in the number of said line.

39. In a telephone system, an automatic connector switch, a party line, a plurality of stations on said line each provided with a set of fixed terminals in said connector,

- means for operating said connector to connect with said line via any set of fixed terminals, and selective ringing mechanism responsive to a single digit in the call number of the wanted station on said line to select a frequency and also to predetermine the set of terminals over which the line is to be seized.
40. In a telephone system, an automatic connector switch, a party line, a plurality of stations on said line each provided with a set of fixed terminals in said connector, means for operating said connector to connect with said line via any set of fixed terminals, and selective ringing mechanism in said connector responsive to a digit in the

call number of the wanted station on said line separate and independent from the digits which control the operation of said connector.

41. In a telephone system, a wiper switch having a relay selector with an auxiliary wiper adapted to complete a circuit from the relay in the succeeding switch over an auxiliary contact-accessible to said wiper, the completing of said circuit causing actuation of said relay for the purpose of switching wipers accessible to bank contacts on said succeeding switch.

Signed by me at Chicago, Cook county, ~~so~~ Illinois, this 1st day of February, 1916.

TRYGVE E. MEYER.
